UNITED STATES PATENT OFFICE.

SAMUEL SUEKOFF, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE REPEATER.

Application filed May 16, 1919. Serial No. 297,468.

To all whom it may concern:

Be it known that I, SAMUEL SUEKOFF, a citizen of the United States of America, residing at Chicago, in the county of Cook 5 and State of Illinois, have invented certain new and useful Improvements in Telephone Repeaters, of which the following is a specification.

My invention relates to transmission systems and has more particularly to do with speech transmission over toll or long distance telephone lines. One of the objects of the invention is to increase the transmission efficiency by means of a simplified 10 repeater circuit arrangement, which may be constructed cheaply yet operate efficiently and require very little maintenance. In long distance transmission circuits, the transmission losses are rated in cable miles, 15 and vary according to the nature and construction of the lines over which the connection is set up, and are often very serious. An object of my invention is the provision of a telephone repeater in which these transmission losses are substantially eliminated. 20

A feature of my invention is the provision of a telephone repeater provided with twin repeater elements substantially identical constituting two-way repeater circuit 25 in which the voice currents are amplified or stepped up to overcome the transmission losses above referred to.

The novel features of the invention through the provision of which the above-mentioned and other advantageous results are attained will be explained by reference to the accompanying drawings in which—

Fig. 1, which comprises parts 1, 2 and 3, illustrates diagrammatically a toll or long distance connection operating in association with the repeater of my invention;

Fig. 2 is a plan view of the voice current relay of my invention;

Fig. 3 is a front elevation of the relay;

Fig. 4 is a right side view of Fig. 2;

Fig. 5 is a view of one of the vibratory members, and

Fig. 6 is a perspective view of the vibratory tongue.

Referring to Fig. 1, part 1, I illustrate a calling local battery substation A connecting at the exchange with the usual drop signal DS and jack J. The magneto cord circuit C comprises an answering plug AP, 50 a calling plug CP and the usual clearing

out drops CD and CD' bridged across the cord conductors; also a listening key LK and a ringing key RK. A trunk jack TJ is shown and its associated drop signal DS' is actuated when a distant exchange wishes 60 connection with a subscriber at the exchange in which the trunk jack TJ is located. This apparatus is associated with the repeater circuit RE of my invention, as illustrated in Fig. 1, part 2.

The repeater circuit RE in Fig. 1, part 2 comprises an operating relay OP, which actuates when a plug is inserted in the trunk jack TJ with which the repeater circuit RE is associated. A chain of relays E, F, H and 70 K is provided, which relays function when relay OP actuates to bring about certain necessary circuit changes in the circuit RE, and a voice current relay VR is also provided, which is included in the chain relay 75 circuit for purposes as will be more fully hereinafter described. A repeating coil RC comprises windings 2, 3 and 4, the said windings 2 and 4 having resistances 5 and 6 in series with them. An amplifier AM 80 comprises an agitating member 7 and an amplifying member 8, and associated with it are the impedance coils 9 and 10. To the right of the repeating coil RC is also a chain of relays E', F', H', and K', which 85 function in a like manner as relays E, F, H and K, and a voice current relay VR' is also provided in association with relays E', F', H', and K', for purposes as will be more fully hereinafter described. To the 90 right of the drawing, I show a ringing key RK' which connects ringing current from the ringing generator G' to throw the drop signal DS' at the distant exchange, which signal is shown with its associated trunk jack TJ' in Fig. 1, part 3. The cord circuit C' of Fig. 1, part 3 comprises an answering plug AP' and a calling plug CP', clearing out drop signals CD' and CD'', a listening key LK', which when actuated 100 connects the operator's set O' to the cord conductors, and a ringing key RK'', which when actuated connects ringing current from ringing generator G''. To the right of the drawing, I show a called substation 105 D comprising the usual local battery substation apparatus, the station terminating at the exchange in a line circuit L' comprising the usual drop signal DS' and its associated jack J'.

Having described in general the apparatus illustrated in Fig. 1, I will now describe in detail the operation of the apparatus used in establishing a connection, including 5 the operation of the repeater circuit of my invention. Assuming that substation A initiates a call, the drop signal DS at the exchange falls and the operator inserts the answering plug AP of the cord circuit C 10 into the jack J, opening the jack spring contacts and disconnecting the drop signal DS from the line. She now actuates her listening key LK to connect her operator's set O to the cord conductors, and inquires 15 the want of the calling subscriber.

Assuming that it is the subscriber D at the distant exchange that is wanted, the operator now inserts the calling plug CP into the trunk jack TJ, leading to the distant 20 exchange and actuates her ringing key RK', connecting generator G', which current actuates the drop signal DS² at the distant exchange (Fig. 1, part 3). The operator at the distant exchange noting the actuated 25 drop signal DS² inserts the answering plug AP' of the cord circuit C' into the trunk jack TJ' associated with the drop signal DS², opening the jack spring contacts and disconnecting the signal DS². She now receives 30 the number of the called substation from the operator at the originating exchange, and as we have assumed that it is substation D that is wanted, the operator inserts the calling plug CP' into the jack J' of that line and actuates the ringing key RK² 35 to connect generator G² to ring the call bell at substation D. The subscriber in response to his call signal, removes his receiver from its switch hook and the subscriber at the calling 40 substation A and the called substation D are now connected and enabled to carry on conversation.

I will now describe in detail the operation of the repeater circuit, as illustrated in Fig. 45 1, part 2. Upon the insertion of the calling plug CP of the cord circuit C into the trunk jack TJ, an energizing circuit for the operating relay OP of the repeater circuit RE is established, traced from battery, through the 50 winding of the operating relay OP, conductor 15, sleeve contact 16 of the jack TJ to ground 17. The operated relay OP closes its alternate contact 18, closing an energizing circuit for the relay F, traced from battery, through the winding of the said relay F, conductor 19, its normal contact 20, conductors 21 and 22, normal contact 23 of relay K, conductor 24, closed contacts 25 and 26 of voice current relay VR, and conductor 27 to ground at alternate contact 18 of relay OP. The relay F' of repeater circuit RE is also energized by current, traced from battery, through the winding of relay F', conductor 19', normal contact 20' of relay F' 60 conductors 21' and 22', normal contact 23'

of relay K', conductor 24', closed contacts 25' and 26' of voice current relay VR', conductors 27' and 27 to ground at alternate contact 18 of relay OP. The relay F upon energization opens its normal contact 20, which removes the shunt about relay E and a series energizing circuit for relays E and F is established, traced from battery, through the winding of relay F, conductors 19 and 28, through the winding of relay E, conductor 22, normal contact 23 of relay K, conductor 24, closed contacts 25 and 26 of relay VR, conductor 27 to ground at alternate contact 18 of relay OP. The closing of alternate contact 29 of relay E closes an energizing circuit for relay H, traced from battery, through the winding of relay H, conductor 30 to ground at alternate contact 29 of relay E. The relay F' upon energization opens its normal contact 20' which removes the shunt about the winding of relay E' and a series energizing circuit is established for relays E' and F', traced from battery, through the winding of the relay F', conductors 19' and 28', through the winding of the relay E', conductor 22', normal contact 23' of relay K', conductor 24', closed contacts 25' and 26' of relay VR', conductors 27' and 27 to ground at alternate contact 18 of relay OP. The closing of alternate contact 29' of relay E' closes an energizing circuit for relay H', traced from battery, through the winding of relay H', conductor 30' to ground at alternate contact 29' of relay E'. The closing of alternate contacts 32 and 33 of relay OP connects the agitating member 7 of the amplifier AM, with the talking conductors 34 and 35, traced from point 36 in conductor 34, over conductor 37, alternate contact 32 of relay OP, conductor 38, through the agitating member 7 of the amplifier AM, conductor 39, alternate contact 33 of relay OP, conductor 40 to the point 41 in conductor 35. The closing of contact 42 of relay OP connects battery to the amplifier member 8, traced from ground at alternate contact 42 of relay OP, conductor 43, through impedance coil 10, conductor 44, winding 3 of repeating coil RC, through the amplifying member 8 of the amplifier AM, through the winding of the impedance coil 9 to battery and ground. The amplifier circuit is thus prepared for amplifying purposes and the impedance coils 9 and 10 in the above-traced circuit are for excluding battery noise and for clarifying the amplified voice transmission currents, as is well understood. The condenser CO is normally bridged across the amplifier circuit, but when relays E and E' are energized, the condenser bridge is disconnected to again be placed in circuit when either party talks, as will be more fully hereinafter described. The above circuit operations all take place when the relay OP is energized, as already 125 130

described. The portion of the circuit to the left of the repeating coil RC and the portion to the right of the repeating coil RC are identical, and both operate in the same manner.

Now assuming that the subscriber at the substation A is the first to talk, the first voice currents that are transmitted pass from the said substation A through the cord connection, over conductor 45, alternate contact 46 of relay E, conductors 47 and 48, through the windings of the voice current relay VR, conductor 49, alternate contact 50' of relay E', conductor 51, alternate contact 52 of relay E to conductor 53 and back to the substation A. The construction of the relay VR is such that the first voice currents that pass through its windings cause it to vibrate its armature and open its closed contacts 25 and 26 to thus open the energizing circuit for relays E and F, and relay E releasing opens contact 29 to allow relay H to de-energize, but relay H being slow to release, its alternate contact 54 is held momentarily closed, closing a circuit for relay K from battery, through alternate contact 54, conductor 55 to ground at now normal contact 56 of E. Relay K is thus momentarily energized, opening its normal contact 23, thus also opening the circuit of relay E. As relay VR picks up, due to voice currents passing through it, its contacts 25 and 26 may possibly vibrate for a fraction of a second before breaking permanently, and relay E might also vibrate in consequence except that relay K in opening its circuit at contact 23 allows relay E to restore with positiveness, and as relay E restores, relay F restores, as does also relay H and the momentarily energized relay K. The chain of relays E, F, H and K are now at normal, but relays E', F' and H' remain energized at this time. The voice currents after relay E restores now pass over conductor 45, normal contact 57, conductor 34 to the point 36 thence over conductor 37, alternate contact 32, conductor 38, through the agitating member 7, conductor 39, alternate contact 33, conductor 40 to the point 41 and from thence over conductor 35, normal contact 58 to conductor 53. The current passing through the agitating member 7, the latter actuates the amplifier member 8 by which it is repeated into the coil 3 and thence into coil 4 of the repeating coil RC. The circuit through coil 3 includes condenser CO and the middle switch contact of relay E. The amplified voice currents now travel from the point 60, over conductor 61, normal contact 80, conductor 62, alternate contact 52' of relay E', conductor 64, normal contact 65 of the key RK' and conductor 66 through the connected substation and back over conductor 67, normal contact 68 of key RK', conductor 69, alternate contact 46', conduc-

tor 47' to the other side of the winding 4 of the repeating coil.

A holding circuit is provided for relay VR in the following manner: A portion of the voice currents is repeated into winding 2 of the repeating coil RC, which voice currents pass from the upper terminal of winding 2 over conductors 47 and 48 through the windings of relay VR, conductor 49, alternate contact 50', conductor 51, through resistance coil 5 to the other terminal of the winding 2. The resistance 5 in series relation with winding 2 regulates the voice current flow through the relay VR and permits only enough current to pass through the said relay to keep it operated and hold contacts 25 and 26 open to prevent relays E, F and H operating while voice currents are traveling toward the called substation D. The resistance 6 is in series relation with the winding 4 of the repeating coil RC, but when relay E restores, due to the opening of contacts 25 and 26 of relay VR, the resistance 6 is shunted out, the said shunt extending from the point 60, over conductor 61, normal contact 80 of relay E, conductor 62 to the point 75 and the amplified voice currents in winding 4 pass out over the talking conductors to the called substation D with full amplified value. The talking circuit through the repeater circuit RE when voice currents are passing from A to D is as follows: over conductor 45, normal contact 57, conductor 34 to the point 36 and thence over conductor 37, alternate contact 32 of relay OP, conductor 38, through the agitating member 7 of the amplifier AM, over conductor 39, alternate contact 33 of relay OP, conductor 40 to the point 41, and thence over conductor 35, normal contact 58 and to conductor 53. The amplified voice currents are now induced in the winding 4 of the repeating coil RC and flow over conductor 61, normal contact 80, conductor 62, alternate contact 58' of relay E', which remains energized when subscriber at substation A is talking, conductor 64, normal contact 65 of key RK' to conductor 66, to the substation D, back over conductor 67, normal contact 68 of key RK', conductor 69, alternate contact 46', conductor 47' to the upper terminal of the winding 4 of repeating coil RC. When the subscriber at substation A stops talking, as at the end of a sentence, voice currents stop passing through the voice current relay VR and contacts 25 and 26 again close, establishing an energizing circuit for relay F, which in turn allows relay E to operate in series with it, the relay E in turn closing a circuit for relay H, as previously described, the relay OP, of course, remaining energized until disconnection takes place.

Assuming now that after the subscriber at the substation A has reached the end of a sentence, the subscriber at the substation

- D begins conversation, the first flow of voice currents will pass through the voice current relay VR' from conductor 67, normal contact 68, conductor 69, alternate contact 46' of relay E', conductors 47' and 48', windings of relay VR', conductor 76, alternate contact 50 of relay E, conductor 62, alternate contact 52', conductor 64, normal contact 65 of key RK' and conductor 66. The relay VR' operates, due to the voice currents passing through its windings, and its contacts 25' and 26' are opened to bring about the de-energization of relay E' in a manner similar to that previously described in connection with relays E, F, H and K. Upon the de-energization of relay E', voice currents now pass through normal contact 57' of relay E', conductor 34 to the point 36, thence over conductor 37, alternate contact 32, conductor 38, agitating member 7, conductor 39, alternate contact 33, conductor 40 to the point 41, over conductor 35, normal contact 58' to conductor 64. The current thus amplified by member 8 is induced from winding 3 into the winding 2 of the repeating coil RC and this amplified current passes from the upper terminal of the winding 2 of the repeating coil RC, conductor 47, alternate contact 46, conductor 45 and through the calling substation A back over conductor 53, alternate contact 52, conductor 51, normal contact 80', conductor 61' to the lower terminal of the winding 2 of the repeating coil RC. The resistance 5 is shunted by the closing of normal contact 80' of relay E', for purposes similar to those already described in connection with resistance 6. A portion of the voice currents is also induced into the winding 4 of repeating coil RC from the upper terminal of winding 4, conductors 47' and 48', through the windings of relay VR', over conductor 76, alternate contact 50 of relay E, conductor 62, through resistance 6 to the other terminal of the winding 4 for the purpose of keeping relay VR' operated to keep the circuits of relays E', F', H' open, for purposes already described.
- During a lull in the conversation in which neither party is talking, a relay VR or VR' restores, depending upon which party talked last, to allow its associated chain of relays E, F, and H or E', F', and H' to again energize and the repeater circuit RE remains thus until either subscriber starts conversation, when one or the other of the twin elements will operate as described, depending upon which subscriber again starts conversation.
- From the above description, it may be seen that I have provided a two-way amplifying repeater with twin repeater elements which operate so that when a calling subscriber is talking after a connection has been established, the portion to the left of the repeat-

ing coil RC restores, and the portion to the right remains actuated to permit amplified voice currents to pass out to the called subscriber. Now, when the called subscriber talks, the portion to the right of the coil RC restores and the portion to the left of the coil remains actuated to permit amplified voice currents to pass out to the calling subscriber. A see-saw action of the two like elements is brought about as the two subscribers alternately talk.

After conversation has terminated, the subscribers at A and D replace their receivers and actuate their hand generators, throwing the clearing out drops CD and CD² at their respective exchanges and the operators at the respective exchanges noting the signal, know that conversation has terminated and withdraw the plugs. The removal of the plug CP from the trunk jack TJ allows relay OP associated with the repeater circuit RE to restore, and relay OP restoring allows relays E, F and H and E', F' and H' to restore, placing circuit RE at normal. The apparatus used in establishing the connection is now at normal and available for establishing other connections.

Assuming now that subscriber at the substation D is the calling subscriber, he actuates his hand generator to throw the drop signal DS³, and the operator inserts the answering plug AP' into the jack J' and actuates her listening key LK'. Assuming that substation A at the distant exchange is wanted, she inserts the calling plug CP' into the trunk jack TJ' leading to the exchange into which the subscriber at the called substation terminates and actuates her ringing key RK² which connects ringing generator current for generator G², the said current passing through the drop signal DS' at the distant exchange, as shown in Fig. 1, part 1. The operator of the exchange with which subscriber A is associated inserts the answering plug AP of the cord C into the trunk jack TJ and receives the number of the subscriber wanted, which we assumed is the subscriber at substation A. The insertion of the calling plug CP into the jack J and the actuation of the ringing key RK connects the ringing generator G to ring the call bell of the subscriber at substation A.

The insertion of the answering plug AP into the jack TJ closes an energizing circuit for the operating relay OP of the repeater circuit RE and the operating relay OP actuating causes the operation of the relays E, F and H and E', F' and H' as already described. Now, when the subscriber at the called substation A answers, the subscribers A and D are in conversational circuit and the repeater circuit will operate in the same manner as previously described, as is also the restoration to normal of the apparatus used in establishing the connection.

Referring now to Figs. 2 to 6 inclusive, I illustrate in detail the voice current relay VR, as described in connection with Fig. 1. The relay as shown comprises a U-shaped magnet 100 suitably supported on a base 101 by means of a yoke member 102, which is secured to the said base 101 by means of screws 103. Magnet coils 104 and 105 are provided and are mounted upon the legs 106 and 107 of the U-shaped magnet 100. A vibrant tongue 108 of thin flexible material is secured at its one end to a bracket 109 by means of the screws 110, the said bracket 109 in turn being secured to the base 101 by means of screws 111. The tongue 108 has a flexible portion 108' and a rigid portion 108² formed by means of the angular extensions 108³, for purposes as will be presently described. The tongue 108 rests at an intermediate point against a stop 112 which is secured to the base 101 by means of screws 113, and the relation of the stop 112 and tongue 108 will be presently described. A pair of pivotally suspended vibratory members 114 and 115 is provided, which are pivotally secured by means of the pivot pins 116 and 117. The pivot pins 116 and 117 are secured to the bracket 118 in any suitable manner, the said bracket 118 being secured to the base 101 by means of the screws 119. The members 114 and 115 are similar in construction and a description of the member 114 is sufficient. The member 114 is constructed of a piece of glass tubing 120 having an enlarged globular end 121 to which a contact 122 is suitably secured, the said contact 122 being connected with the terminal 123 by means of the wire connection 124 which passes through the central opening of the member 114. The member 114 is also provided with a hooked or looped end 125 by which the said member is supported on its pivot pin 116.

The free end of the tongue 108 is provided with a pair of contacts 126 and 127, which are normally in engagement with the contacts 122 and 128 on the respective vibratory members 114 and 115.

The relay VR is affected by voice currents and operates through the different ranges of frequencies of voice currents, the range being 216 for the lowest and 1500 for the highest. The natural rate of vibration of the members 114 and 115 is below the lowest rate of the voice currents and when voice currents pass through the coils 104 and 105, the tongue is set into vibration, and this vibration of the tongue 108 being permitted, due to its flexible portion 108'. The end 108⁴ of the tongue 108 is also set into vibration, due to the stop 112 being in engagement with the tongue and this vibration forces the members 114 and 115 apart. As the natural rate of vibration of the members 114 and 115 is lower than the lowest rate of the voice currents, the said members are kept apart, due to the vibration of the end 108⁴ of the tongue keeping the contacts 126, 122, 127 and 128 open as long as voice currents are passing through the magnet coils 104 and 105 for purposes already described in connection with Fig. 1.

The lines A and D may be toll lines instead of subscribers' lines. By constructing the relays in a desired manner, I find that they may be made to work with great dispatch and accuracy, thereby causing a very efficient operation of the circuit arrangement.

While I have illustrated my invention operating in connection with a specific circuit arrangement, I do not wish to be limited to the same as the circuit of my invention is applicable with other circuit arrangements, and I also do not wish to be limited to the exact arrangement as shown, as many changes and modifications are readily apparent, and I, therefore, aim to cover all such changes and modifications as come within the spirit and scope of the appended claims.

Having described my invention, what I claim as new and desire to secure by United States Letters Patent, is:

1. A system of the character described including a calling telephone and a called telephone, a circuit for connecting said telephones, a voice current relay and a repeater for said circuit, said repeater including an agitating member and an amplifying member, means controlled by said voice current relay for connecting said agitating member to the calling telephone and the amplifying member to the called telephone, a primary energizing circuit for said voice current relay including said calling telephone, and another circuit for said voice current relay for maintaining said relay energized independently of said primary energizing circuit during transmission of voice currents from said calling telephone.

2. A system of the character described including a calling telephone and a called telephone, a circuit for connecting said telephones, a pair of voice current relays, and a repeater for said circuit, means including a chain of relays controlled by one of said voice current relays for connecting said repeater so that the voice currents transmitted from the calling telephone are amplified and retransmitted to the called telephone, means including a chain of relays controlled by said other voice current relay for connecting said repeater so that the voice currents transmitted from the called telephone are amplified and retransmitted to the calling telephone, a primary energizing circuit for said one relay including said calling telephone line, another circuit for maintaining said one relay energized independently of said primary energizing circuit when voice

currents are being amplified and retransmitted to the called telephone, a primary energizing circuit for said other relay including said called telephone, and another circuit for maintaining said other relay energized independently of said second primary energizing circuit when voice currents are being retransmitted to the calling telephone.

3. A system of the character described including a calling microphone and a called telephone, a circuit for connecting said microphone and said telephone including a voice current relay normally disconnected from said circuit and a telephone repeater, said voice current relay when connected in said circuit being responsive to talking currents transmitted from said calling microphone over a circuit including said calling microphone to connect said telephone repeater in circuit so that the said voice currents are amplified and retransmitted to the called telephone, and a circuit for inductively receiving said talking currents for maintaining said relay operated independently of the circuit including said calling microphone.

4. A system of the character described including a calling telephone and a called telephone, a two-way trunk circuit for connecting said telephones, a pair of voice current relays, a telephone repeater including an agitating member and an amplifying member for said circuit, relay mechanism associated with each of said voice current relays, means controlled by one of said voice current relays and its associated relay mechanism for effectively connecting the agitating member of said repeater in series circuit with the calling telephone and the amplifying member of said repeater to the called telephone when voice currents are transmitted from the calling telephone, and means controlled by the other of said voice current relays and its associated relay mechanism for connecting the agitating member of said repeater in series circuit with the called telephone and the amplifying member of said repeater to the calling telephone when voice currents are transmitted from the called telephone.

5. A system of the character described including a calling telephone and a called telephone, a trunk circuit for connecting said telephones, a pair of voice current relays and a repeater for said trunk circuit, said repeater comprising an agitating member and an amplifying member, relay mechanism associated with each of said voice current relays, means controlled by one of said voice current relays when voice currents are transmitted from said calling telephone to operate said relay mechanism to effectively connect the agitating member of said telephone repeater in series circuit with the calling telephone and the amplifying member of the repeater to the called telephone, said

voice current relay operating to maintain the circuit in this condition as long as voice currents are transmitted from the calling telephone, said other voice current relay being operative when voice currents are transmitted from the called telephone to operate its associated relay mechanism to connect the agitating member of said repeater in series circuit with the called telephone and the amplifying member of said repeater to the calling telephone, said circuit remaining in this condition as long as voice currents are transmitted from the called telephone.

6. A telephone system of the character described including a calling telephone and a called telephone, a circuit for connecting said telephones, a telephone repeater for said circuit, and mechanism including a chain of relays for said circuit operative to connect said repeater in circuit so that when voice currents are transmitted from the calling telephone the repeater operates to amplify the voice currents and retransmits them to the called telephone and when voice currents are transmitted from said called telephone the repeater is connected so that the voice currents are amplified and retransmitted to the calling telephone, two relays in said chain of relays controlling contacts in the voice current conductors of said circuit.

7. A telephone system of the character described including a calling telephone and a called telephone, telephone lines for said calling and called telephones, a circuit for connecting said telephones, a repeater including an agitating member and an amplifying member, and mechanism for said circuit controlled by the voice currents transmitted from the calling and called telephones for connecting the agitating member of the repeater in series circuit with telephone lines of the calling telephone and the amplifying member to the called telephone when the microphone of the calling telephone is operated to transmit voice currents, and for connecting the agitating member of the repeater in series circuit with the telephone lines of the called telephone and the amplifying member of the repeater to the calling telephone when the microphone of the called telephone is operated to transmit voice currents.

8. A system of the character described including a calling telephone and a called telephone, a circuit for connecting said telephones, a telephone repeater for said circuit normally disconnected from said calling telephone and said called telephone, and voice-current-controlled mechanism including a chain of relays for connecting said repeater so that when the subscriber at the calling telephone talks, the voice currents will be amplified by the repeater and transmitted to

the called telephone and when the subscriber at the called telephone talks, the voice currents will be amplified and transmitted to the calling telephone, two relays of said 5 chain of relays controlling contacts in the voice current conductors of said circuit.

9. A telephone system of the character described including a calling and a called telephone, a circuit for connecting said telephones, a voice current relay adapted to be connected across the calling telephone, a telephone repeater having an agitating and an amplifying member, means controlled by said voice current relay for connecting said 10 agitating member in series circuit with the calling line and said amplifying member across the called line.

10. A telephone system of the character described including a calling and a called telephone, a circuit for connecting said telephones, a voice current relay adapted to be connected across the calling telephones, a telephone repeater having an agitating and an amplifying member, means controlled by 15 said voice current relay for connecting said agitating member across and in series circuit with the calling line and said amplifying member across the called line, said means being also operative to remove the 20 voice current relay from across the calling telephone and for inductively connecting it to the calling telephone.

11. A system of the character described including a calling telephone and a called 25 telephone, a link circuit including a pair of voice current relays for connecting said telephones, a repeater for said circuit having an agitating and an amplifying member, means for bridging one of said voice current relays across the calling telephone and the other of said relays across the called telephone, means controlled by one of said 30 voice current relays when voice currents are transmitted from the calling telephone for removing both of said voice current relays from across the calling and called telephone, 35 respectively, and for connecting the agitating member of said repeater to the calling telephone and the amplifying member of said repeater to the called telephone.

50

12. A system of the character described including a calling telephone and a called telephone, a link circuit including a pair of voice current relays for connecting said telephones, a repeater for said circuit having an agitating and an amplifying member, means for bridging one of said voice current relays across the calling telephone and the other of said relays across the called telephone, means controlled by one of said voice current relays when voice currents are transmitted from the calling telephone for removing both of said voice current relays from across the calling and called telephone, respectively, and for connecting the agitating member of said repeater to the calling telephone and the amplifying member of said repeater to the called telephone, and means controlled by said other voice current relay when current is transmitted from the called telephone for disconnecting the voice current relays from across the telephones and for connecting the agitating member of said repeater to the called telephone and the amplifying member of said repeater to the calling telephone. 55 60 65 70 75

13. A system of the character described including a calling telephone and a called telephone, a link circuit including a pair of voice current relays for connecting said telephones, a repeater for said circuit having an agitating and an amplifying member, means for bridging one of said voice current relays across the calling telephone and the other of said relays across the called telephone, means controlled by one of said voice current relays when voice currents are transmitted from the calling telephone for removing both of said voice current relays from across the calling and called telephone, 80 85 90 95 respectively, and for connecting the agitating member of said repeater to the calling telephone and the amplifying member of said repeater to the called telephone, and for inductively connecting said voice current relay to said calling telephone.

Signed by me at Chicago, in the county of Cook and State of Illinois, this 14th day of May, 1919.

SAMUEL SUEKOFF.
